UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A LADY'S BASQUE.

SPECIFICATION forming part of Design No. 14,432, dated November 20, 1883.

Application filed August 23, 1883. Term of patent 3½ years.

To all whom it may concern:

Be it known that I, CATHERINE O'HARA, of the city, county, and State of New York, have invented and produced a new and original Design for a Pattern of a Lady's Basque, (numbered 8,827;) and I do hereby declare that the engraved prints accompanying this specification convey to any one accustomed to using paper patterns a clear understanding 5 of how a garment made up by the pattern will appear.

The design combines a closely-fitted front, cutaway below the closing, and a closely-fitted

back with fan-plaitings inserted in the lower parts of its middle three seams, coat-sleeves 15 and a standing collar being added.

What I claim as my invention, and desire to secure by Letters Patent, is—

The design for a lady's basque, as shown in the engraved prints accompanying this 20 specification.

CATHERINE O'HARA.
